UNITED STATES PATENT OFFICE.

WILBURT C. TRUSSELL, OF BOSTON, MASSACHUSETTS.

CAR-STARTER.

SPECIFICATION forming part of Letters Patent No. 293,119, dated February 5, 1884.

Application filed December 10, 1883. (No model.)

To all whom it may concern:

Be it known that I, WILBURT C. TRUSSELL, a citizen of the United States, residing at Boston, in the county of Suffolk and State of Massachusetts, have invented a new and useful Improvement in Car-Starters, of which the following is a specification.

The object of my invention is to provide an improved means for relieving the horses attached to a street-car of the strain of the dead-pull in starting the car after a stoppage.

In the accompanying drawings, which form a part of this specification, Figure 1 represents a longitudinal vertical section of a street-car to which my invention is applied. Fig. 2 is a bottom or under side view. Fig. 3 is an enlarged detail view of the main feature of the invention.

Similar letters indicate like parts in the several figures.

a is the body of an ordinary street-car. *b b* are the wheels, and *c* the axles.

To the axle *c* is firmly secured a ratchet-wheel, *d*, which may be of any required diameter. *e* is an arm or lever, which is connected with a frame or yoke, *t*, attached to the axle *c*, so as to turn freely on the same, as shown in Fig. 3. The ratchet-wheel *d* is made in two parts, so as to enable it to be readily attached to the axle of the wheels without removing the latter from the axles. The two parts of the ratchet-wheel are bolted together, as indicated at *d'*, Fig. 3.

To the frame or yoke *t* is pivoted a pawl, *i*, which engages with the ratchet-wheel *d*. Underneath the pawl *i* is a spring, *k*, which serves to keep the pawl off from contact with the ratchet-wheel *d* when not in use.

To the free end of the arm *e* is attached a rope or chain, *f*, which passes up over a pulley, *h*, in a frame, *o*, which is allowed a sliding motion, so as to adapt the rope to movement of the arm *e*. The rope *f* passes forward, and is attached to a pulley-block, *n*. To the pulley-block *n* is attached a rope, *f'*, which passes through a pulley-block, *m*, having a double purchase, and, extending forward, is attached to a draw-head, *r*, which slides in a clevis, *s*.

Over the end portion of the arm *e* is a cross-piece, *u*, through the ends of which pass rods

or bars *g*, secured to a cross-piece, *u'*, above. Surrounding the rods *g* are coiled springs, which serve to hold the arm *e* down. The normal position of the pawl *i* is away from contact with the ratchet-wheel *d* when the wheels and axle are in motion in the ordinary running of the car, owing to the spring *k*. To bring the pawl into contact with the ratchet-wheel *d*, a cord, *l*, is attached to the pawl *i*, and, passing through a hole in one of the arms or sides of the yoke *t*, is carried back and attached to the rope *f*, as shown.

To the draw-head *r* is attached a whiffletree or single-tree, connected with the pole when the latter is employed.

The pulley-blocks *m* and *n* may be dispensed with, and the rope *f* may extend from the pulley *h* to the draw-head *r*.

When the car is at a standstill, it will be seen that the arm *e* will be depressed by means of the springs on rods *g*. Immediately as the draft is applied to the draw-head *r* by the starting of the horses the rope *f* will be tightened and raise up the arm *e*. The pawl *i* will then engage with the ratchet-wheel *d* and cause the wheels to rotate, and thus effectively serve to start the car with the expenditure of much less power or strain upon the horses than if the power is applied directly to drawing the car, as usual.

I have described the above as applied to one set of wheels only. It will of course be understood that the same arrangement is to be applied to the other set of wheels to provide for the car going in the opposite direction.

Instead of the starting arrangement being effected by the draft of the horses, it may be effected by the driver, in which case the rope *f* will be operated by means of a windlass and pawl and ratchet connected to a crank-bar arranged similarly to that by which the brakes are operated. More than one ratchet-wheel and its connections may be connected with the axle.

My invention can be readily applied to street-cars, now in use without the necessity of changing any part of their construction.

What I claim as my invention, and desire to secure by Letters Patent, is—

In a car-starter, the combination of the slid-

ing draw-head *r* on the clevis *s*, the rope *f'*, pulley-blocks *m n*, rope *f*, pulley *h*, and sliding frame *o*, lever *e* and yoke *t*, pawl *i*, and ratchet-wheel *d*, secured to the axle *c*, all operating conjointly, substantially as and for the purpose specified.

In testimony whereof I have signed my name

to this specification in the presence of two subscribing witnesses.

WILBURT C. TRUSSELL.
